CABLING STRAP

Samuel P. Hull, Yonkers, N. Y., John J. Corcoran, Cleveland, Ohio, and Beverly A. Lundy, Larchmont, N. Y.; said Lundy assignor to Railroad Accessories Corporation, New York, N. Y., a corporation of New York

Application December 3, 1942, Serial No. 467,740

7 Claims. (Cl. 243—61)

This invention relates to conductors and particularly to conductors known as cables and more especially to a means which will be designated, a cabling strap, for securing the separate conductors of a cable together and supporting them or for supporting a plurality of conductors which have already been made into the form of a cable.

A principal object of this invention is the provision of a device of the type specified which will be inexpensive to manufacture, easy to apply, efficient in use, and not harmful to the separate conductors making up a cable and of a design such that there is sufficient supporting area to prevent cutting of the cable by the cabling strap.

A further object of the invention is the production of a device of the type specified which will electrically insulate the cable from the messenger wire or cable.

A further object of this invention is a provision of a device of the type specified which will be particularly resistant to deterioration or corrosion from atmospheric conditions.

A further object of the invention is the production of a device of the type specified which will be so constructed that it will be equally effective whether wrapped clockwise or counter-clockwise about a cable.

Other objects and advantages will appear as the description of the particular physical embodiment selected to illustrate the invention progresses and the novel features of the invention will be particularly pointed out in the appended claims.

In describing the invention in detail, and the particular embodiment selected to illustrate the invention, reference is had to the accompanying drawings, wherein has been illustrated the particular preferred physical embodiment of the invention, and wherein like characters of reference designate corresponding parts throughout several views, and in which:

Figure 1 is a front elevational view of a device constructed in accordance with our invention applied to a preformed cable supported by a messenger wire; Fig. 2 is a view of the device, as shown by Fig. 1, as looked at from the right hand side, with some parts broken away to more clearly illustrate the construction; Fig. 3 is a cross sectional view of the device of Fig. 1, on the plane indicated by the line III—III, viewed in the direction of the arrows at the ends of the line; Fig. 4 is a front elevational view of that portion of our invention which is adapted to hook over a messenger wire; Fig. 5 is a front elevational view of that form of our invention used for support-

ing a cable which is formed by the assemblage or bunching of conductors together with or without a central messenger wire; Fig. 6 is a cross sectional view of the device as shown by Fig. 5, on the plane indicated by the line VI—VI of Fig. 5, viewed in the direction of the arrows at the ends of the line; Fig. 7 is a detail view of that portion of our invention which will be designated as the cable wrap; Fig. 8 is a cross sectional view of the device, as shown by Fig. 7, on the plane indicated by the line VIII—VIII of Fig. 7, viewed in the direction of the arrows at the ends of the line.

An ordinary and conventional construction of cable and messenger wire is illustrated in Fig. 1, where 1 designates a preformed cable or assemblage of electrical conductors such as 2. This cable 1, conventionally, may have a sheath of metal entirely surrounding it or present merely insulating material on its periphery.

15 Numeral 3 designates a messenger wire or cable which is conventionally used to support the cable including the electrical conductors 2.

20 By our invention we provide a messenger wire hook designated as a whole by 4 and shown in detail in Fig. 4. This messenger wire hook is formed from substantially flat bar stock 5 by bending and forming. It is bent into a hook, as best illustrated by Fig. 4, so that there is a semi-circular portion 6 terminating in substantially parallel ends 7 and 8. This semi-circular portion 6 is made of various radii so as to conform substantially to the radius of the particular messenger wire with which it is intended it shall be

25 used. Each edge of the bar stock 5 is turned at a right angle so as to form edge ribs, 9 and 10, as well shown in Fig. 2. A median rib 11 is struck up from the center of the bar stock to further strengthen the hook. On each edge of the bar stock just below the termination of the edge ribs 9 and 10, two ears, 12 and 13, are formed projecting substantially in the plane of the side ribs 9 and 10 and at a right angle to the general flat surface of the bar stock. Below the ears 12 and

30 13 the bar stock is formed with marginal struck up ribs 14 and a tail end 15 is provided which is adapted to be forced into parallelism with the depending portion 16 of the hook and may then be secured in position by folding over the ears 12 and 13 thereupon. There is provided a shoulder

35 17 at the end of the tail 15 to prevent the tail from drawing downwardly out of engagement with the ears 12 and 13 after they have been pressed into place against the tail.

40 45 50 55 The hook member 4 forms the means for sup-

porting the cable wrapping member designated as a whole by 18.

The cable wrap or strap 18 includes a central stringing flexible rod or wire 19, as best shown in Fig. 7. This stringing wire 19 extends from the outer face of an end block 20 to the outer face 21 of the end block of the opposite end of the strap. This stringing wire 19 is preferably made of metal, and preferably of a metal or metal alloy resistant to atmospheric conditions to the end that it will be immune to corrosion. It may well be made of galvanized iron or phosphor bronze. This wrapping wire 19 is preferably formed with slight depressions, nicks, serrations, or indentations, as 22, for the purpose of the more securely holding blocks, to be later described, which are molded thereon.

Spaced somewhat apart along the stringing wire 19 are small somewhat rectangular blocks or beads 23. These blocks are of insulating material and preferably made of a thermo plastic resin such as Bakelite. These blocks are preferably molded in place on the stringing wire 19. Each block is molded with the two orifices therethrough, as 24 and 25, best shown in Fig. 8. Each block has its opposite faces, of which in practice one of the other contacts the outside of a cable, preferably formed with minute serrations, as 26 and 27, parallel with the stringing wire 19.

After the beads or blocks 23 have been formed in place on the stringing wire 19 the two ends of an attaching wire 28 are passed through the orifices 24 and 25 of all of the blocks 23, as best shown in Fig. 7. This attaching wire 28 is formed into a supporting loop 29 at one end of the bends 23 providing a stretcher portion 30 which is adapted to seat on the hook 4 substantially at the junction between the portions 16 and the tail 15 it also has bulging ends. This attaching wire, so formed, when seated in portion between 16 and 15 is, due to its form restrained from displacement endwise, due to the curved ends 31 and 32 of the attaching wire contacting the edges of the tail piece 15.

In practice, the portion 30 is placed on the tail 15 of the hook and the tail brought up into the parallelism with the portion 16 of the hook and the ears 12 and 13 pressed down into place over the tail 15 as best shown in Figs. 1 and 2. This is all preferably done at the factory or place of manufacture.

When it is desired to support a cable on a messenger wire, the wrapping 18 is wrapped about the cable to be supported bringing the free ends, 33 and 34, in contact with the wire 28 just over the curved portions 35 and 36, respectively, and extending beyond, then the free ends are twisted together so as to form a twisted tail 37, as best shown in Fig. 1.

After the wrapping has been completed and the tail ends secured, the messenger wire hook 4 is hooked over the messenger wire 3.

In some cases the messenger wire, if used, is positioned in the center of the cable or no messenger wire at all is used but reliance is placed upon the strength of the metallic conductors themselves to support themselves. In such case the wrap 18 merely serves to compactly and rigidly hold all of the conductors together. In such case, hook 4 is not used at all.

When the form, as shown in Fig. 5 is employed, a tube 38 is placed over the portion 30 of the attaching wire 28 prior to forming that attaching wire into the form as shown in Fig. 7. This tube is preferably made of fairly heavy copper

and is formed with flanged ends, as at 39 and 40. With this tube in place on the portion 30 twisting the ends of the attaching wire 28 together to form the twisted tail 37 will not draw the portions 35 and 36 together in such a way that the free ends 33 and 34 may slip up over curves 31 and 32.

The entire device is made of material which will not corrode when exposed to atmospheric conditions. The hook 4 is preferably made of a bronze which is substantially resistant to atmospheric conditions. The stretcher wire 19, as stated, is preferably made of material resistant to atmospheric conditions. The blocks 23 have been found, when made of Bakelite to be resistant to weather conditions. The attaching wire 28 is preferably made of phosphor bronze which is resistant to weather conditions and the flanged tube 38 is preferably made of copper which is also resistant to weather conditions.

The minute serrations or roughening of the blocks or beads 23 is such that the material of the cable supported will not be abraded by any tendency of the cable to move longitudinally on the messenger wire but at the same time the serrations prevent relative movement of the supported cable and messenger wire hook so that "bunching" of the hooks 4 is prevented.

It is to be noted that, in the field, the strap 30 may be shortened by breaking and removing more or less of blocks 21 and shortening, if thought necessary, wire ends 33 and 34 or the strap may have additional blocks 21 placed on the ends 33 and 34 to the extent made possible by their length 35 after allowance is made for the wire necessary to form the twisted ends.

Although we have particularly described one particular physical embodiment of our invention, and a modification thereof, nevertheless, we desire to have it understood that the form selected is merely illustrative but does not exhaust possible physical embodiments of the idea of means underlying our invention.

What we claim as new and desire to secure by Letters Patent of the United States, is:

1. A cabling device, including, in combination: a stringing wire formed with serrations; a plurality of beads, spaced apart, formed of insulating material formed in place on said wire each bead formed with two spaced through orifices, one on each side of the stringing wire and adapted to receive an attaching wire; an attaching wire bent with its ends parallel and positioned, one end in one orifice of each block and the other end in the other orifice of each block, said wire formed into a loop at its median portion, said loop providing bulging ends whereby the said members may be wrapped about a cable and the free ends of the attaching wire may be passed one on one side 55 of the one bulge of the loop and the other on the remote side of the other bulge of the loop and be twisted together.

2. A cabling device, including, in combination: a stringing wire formed with serrations; a plurality of beads, spaced apart, formed of insulating material formed in place on said wire each bead formed with two spaced through orifices, one on each side of the stringing wire and adapted to receive an attaching wire; an attaching wire bent with its ends parallel and positioned, one end in one orifice of each block and the other end in the other orifice of each block, said wire formed into loop at its median portion, said loop providing bulging ends whereby the said members 65 may be wrapped about a cable and the free ends 70 of the one bulge of the loop and the other on the remote side of the other bulge of the loop and be twisted together.

of the attaching wire may be passed one on one side of the one bulge of the loop and the other on the remote side of the other bulge of the loop and be twisted together, and means for hanging said loop to a messenger wire.

3. A cabling device, including, in combination: a stringing wire formed with indentations; a plurality of beads, said beads being positioned on said stringing wire along its length and spaced apart, each of said beads formed with two through orifices, said orifices having their longitudinal axis parallel with said stringing wire and one positioned on one side of said stringing wire and the other positioned on the other side of said stringing wire; an attaching wire, said attaching wire including a loop having a bulging portion at each end and having two substantially parallel free end portions extending from the loop, one of the end portions extending through the orifices in the beads on either side of the stringing wire whereby a cable strap is formed which may be wrapped about a cable with the beads in contact with the cable and whereby the free ends of the attaching wire may be passed one under one bulge of the loop and the other under the other bulge of the loop and then be twisted together whereby a cable will be firmly held.

4. A cabling device, including, in combination: a stringing wire formed with indentations; a plurality of beads, said beads being positioned on said stringing wire along its length and spaced apart, each of said beads formed with two through orifices, said orifices having their longitudinal axis parallel with said stringing wire and one positioned on one side of said stringing wire and the other positioned on the other side of said stringing wire; an attaching wire, said attaching wire, including a loop having a bulging portion at each end and having two substantially parallel free end portions extending from the loop, one of the end portions extending through the orifices in

the beads on one side of the stringing wire and the other end portion extending through the orifices in the beads on the other side of the stringing wire whereby a cable strap is formed which may be wrapped about a cable with the beads in contact with the cable and whereby the free ends of the attaching wire may be passed one under one bulge of the loop and the other under the other bulge of the loop and then be twisted together whereby a cable will be firmly held, and means adapted for supporting the loop from a messenger wire.

5. A cabling strap, including, in combination: a plurality of insulating beads; means maintaining said beads in line and in spaced relation; means passing through each of the beads and providing free ends one of which is in the form of a supporting loop and the other of which consists of two ends which may be twisted together after being passed one on one side of the loop and the other on the other side of the loop.

6. A bead for a cabling strap formed of insulating material and provided with serrations on opposite faces thereof and provided with through orifices one on each side of the center thereof.

7. An attaching wire for supporting a cable from a messenger wire hook having a loop with a bulge at each end adapted to receive the hook and having two substantially parallel portions extending from the loop adapted to be passed through spaced aligned insulating beads, one of said parallel portions being positioned under the bulge at a distance from the free end and the other parallel portion being positioned at the other bulge at a distance from the free end and the parts of the parallel portion between the free ends and the bulge being twisted together.
